WALTER HARNISCHFEGER, OF MILWAUKEE, WISCONSIN, ASSIGNOR TO HARNISCHFEGER CORPORATION, OF MILWAUKEE, WISCONSIN, A CORPORATION OF WISCONSIN

SELECTIVE DRIVE FOR EXCAVATING MACHINES

Application filed March 29, 1928. Serial No. 265,760.

This invention relates to general to excavating machinery and more particularly to a selective drive control for such machines.

Excavating machines, such as power shovels, power hoes, and the like have their various instrumentalities such as their drums, swing gear and traction means driven from a single power plant which frequently, in the modern type of machine, is a gasoline engine, 10 Diesel engine or other type of internal combustion engine. In some localities and in the construction of subway tunnels and the like, it is impractical or dangerous to use an internal combustion engine, as the exhaust gases constitute a menace to health and life. Under such circumstances, it becomes desirable to employ a power plant of the type of an electric motor.

One of the principal objects of the present 20 invention is to provide an excavating machine which may selectively employ as its power plant, either an internal combustion engine or an electric motor. In other words, two different types of power plant are provided and either may be used to actuate the various instrumentalities of this machine.

Another object of the present invention resides in the provision of a novel drive control whereby either type of power plant may 30 be brought into action by simply manipulating a control lever common to the two power plants and operable to disconnect either power plant from the instrumentalities of the machine, or to connect either power plant selectively thereto.

Another object of the invention resides in the provision of a selective drive control of this character which is of simple and durable construction, reliable and effective in operation and easy to operate.

Other objects and advantages reside in certain novel features of the construction, arrangement and combination of parts which will be hereinafter more fully described and particularly pointed out in the appended claim, reference being had to the accompanying drawings forming a part of this specification, and in which:

Figure 1 is a fragmentary plan view showing the invention applied to an excavating

machine, parts being broken away for the sake of illustration;

Figure 2 is a view in side elevation of the parts shown in Figure 1;

Figure 3 is a view in front elevation looking toward the left hand side of Figure 1, parts being broken away and parts being shown in section along line 3—3 of Figure 1 for the sake of illustration; and

Figure 4 is a detail view of the control mechanism removed from the power plants.

Referring to the drawings, the numeral 1 designates diagrammatically a portion of the revolving platform of an excavating machine which may be a power shovel or any other type of excavating machine. On 65 this platform, an internal combustion engine is provided and a portion of such engine is designated at 2. An electric motor 3 is also mounted on the platform. It is proposed 70 to selectively drive the instrumentalities of the machine from the internal combustion engine 2 or from the electric motor 3. The drive is imparted to a large gear wheel 4 which is connected to the various instru- 75

mentalities in the usual way. In carrying out this purpose, the engine shaft 5 of the internal combustion engine 2 has a pinion 6 loosely mounted thereon and constantly meshing with the large gear 80 wheel 4 of the excavating machine. This pinion 6 has a jaw clutch member 7 integral therewith or rigidly connected thereto. A driving jaw clutch member 8 is splined on the engine shaft 5 and is adapted to engage or interfit with the jaw clutch member 7 to 85 connect the pinion 6 to the engine shaft 5 and thereby actuate the gear 4 from the internal combustion engine.

The electric motor 3 has an armature shaft 90 10 on which a pinion 11 is loosely mounted, the pinion 11 constantly meshing with the gear wheel 4 at a point spaced from the pinion 6. This pinion 11 has a jaw clutch member 12 integral therewith or rigidly connected thereto and adapted to engage or interfit with a similar driving jaw clutch member 13 splined on the armature shaft 10 and operable when engaged with the jaw clutch member 12 to constrain the pinion 11 100

to rotate with the armature shaft 10 and consequently to drive the gear 4 from the electric motor.

The present invention proposes a common control for the sliding clutch members 8 and 13 which so co-ordinates or moves all these clutch members as to permit either, but not both, to be engaged with their co-operable clutch members as well as to permit both sliding clutch members to be disengaged. In carrying out this purpose, the clutch member 8 has a grooved hub 15 which receives the arcuate trunnion blocks 16 of a shifter fork 17, the shifter fork 17 being integrally formed with the bearing member 18 which is fixed to a shifter shaft 19 journaled in bearing brackets 20 provided on the revolving platform of the machine.

Similarly the sliding clutch member 13 has a grooved hub 21 receiving the arcuate trunnion blocks 22 of a shifter fork 23 integrally formed on a socket bearing member 24 which receives one end of a shifter shaft 25 journaled in a bearing 26 formed on an extension 27 of one of the brackets 20. The shafts 19 and 25 are connected or linked together so as to be constrained to partake of their co-ordinated motions and this connection of the shafts is effected by securing crank arms 28 and 29 to the shafts 19 and 25, respectively, and pivotally connecting the ends of these crank arms to the ends of an adjustable link or an adjustable connecting rod 30. The crank arms 28 and 29 extend in opposite directions so that the motion of the shaft 25 is reversed with respect to the motion of the shaft 19. While the connecting rod or link 30 is adjustable, when once adjusted, it has all the characteristics of a rigid, inextensible link.

A single control lever, designated at 35, is provided and is fixed to one end of the shaft 19 adjacent one of the bearings 20. This lever 35 may have any means for releasably holding it in any one of its three positions and for this purpose, a segmental plate 36 may be secured to the adjacent bearing 20 and may have three spaced sockets or recesses 37 with which a spring pressed plunger on the lever releasably engages to prevent accidental displacement of the lever. A portion of a gear casing is shown at 50 in Figure 3 and is outlined diagrammatically in Figures 1 and 2.

With this control, when the lever 35 is positioned as shown in full lines in Figure 3, clutch members 8 and 13 are both disengaged from their respective co-operable clutch members 7 and 12. This is the neutral position of the control and at such time the gear 4 is not driven from either of the power plants. If the lever 35 is shifted to the right as viewed in Figure 3, to the dotted line position illustrated, the clutch member 8 will be moved farther away from its clutch member

7 as the shaft 19 is turned in a clockwise direction as viewed in Figure 3 and similarly rotates the shifter 17. The crank arm 28 partakes of this motion of the shaft 19 and acts through the link 30 to rotate the crank arm 29 and the shaft 25 in a counter-clockwise direction as viewed in Figure 3, thereby causing the shifter fork 23 to slide the clutch member 13 to the left as viewed in Figure 3 and into engagement with the clutch member 12. This connects the pinion 11 to the armature shaft 10 and provides an operative connection between the electric motor and the excavating machine.

If the control lever 35 is shifted to its other extreme position, that is, is moved in a counter-clockwise direction as viewed in Figure 3, then the clutch member 8 is moved to the right and into engagement with its clutch member 7 while the clutch member 13 is moved to the right as viewed in Figure 3 and away from its clutch member 12. At such time the internal combustion engine is operatively connected to the excavating machine and the electric motor is disconnected.

I claim:

In an excavating machine of the type having a platform, an internal combustion engine mounted on the platform and having an engine shaft, and an electric motor mounted on the platform and having an armature shaft, means for selectively driving the instrumentalities of the excavating machine from the engine shaft or the armature shaft and comprising a pinion loosely mounted on the engine shaft, a clutch for connecting the pinion to the engine shaft, a pinion loosely mounted on the armature shaft, a clutch for connecting the pinion to the armature shaft, a gear wheel on the excavating machine with which the pinions constantly mesh, a single control member and means between the control member and the clutches for causing one clutch to be disengaged when the other is engaged whereby the gear wheel may be driven selectively by said internal combustion engine or by said electric motor.

In witness whereof, I hereto affix my signature.

WALTER HARNISCHFEGER.
